UNITED STATES PATENT OFFICE.

ALBERT J. THORNLEY, OF PAWTUCKET, ASSIGNOR TO THE CONSOLIDATED CAR FENDER COMPANY, OF PROVIDENCE, RHODE ISLAND.

CAR-FENDER.

SPECIFICATION forming part of Letters Patent No. 548,019, dated October 15, 1895.

Application filed June 26, 1895. Serial No. 554,116. (No model.)

To all whom it may concern:

Be it known that I, ALBERT J. THORNLEY, of the city of Pawtucket, in the county of Providence and State of Rhode Island, have 5 invented certain new and useful Improvements in Car-Fenders; and I hereby declare that the following is a full, clear, and exact description of the same, reference being had to the accompanying drawings, forming part 10 of this specification.

This invention has reference to improvements in car-fenders of the nature described in United States Letters Patent No. 534,982, granted to me February 26, 1895.

15 The invention relates particularly to the device for releasably supporting the fender-sustaining lever.

The object of the invention is to so construct the sustaining-lever-supporting device 20 that the lever may be locked in two positions.

Another object is to so construct this supporting device that both locking-latches may be actuated by the same mechanism.

25 Another object of the invention is to so construct a supporting device of this nature that it may be used in combination with a removable sustaining-bar.

The invention consists in the combination with a fender-sustaining lever of a locking-latch adapted to engage the lever when the 30 lever is in either the raised or depressed position.

The invention also consists in the oppositely-disposed latches and in the means for 35 simultaneously actuating them.

The invention also consists in a supporting-bracket having a slot open at the lower end between diverging lips and a double-latching device located to act in the slot.

40 The invention consists in such other novel features of construction and combination of parts as may hereinafter be more fully described, and pointed out in the claims.

Figure 1 represents a side elevation of the 45 supporting device removed from the car, the fender-sustaining lever being shown in two positions. Fig. 2 represents a cross-sectional view of the same.

Similar numbers of reference designate corresponding parts throughout.

In carrying my invention into practice it

has been my desire to positively lock the fender either in the depressed or in the raised position, as when the fender is in the depressed position a sudden shock to the same, 55 by passing over an obstruction before reaching the object it is designed to catch, will throw the fender upward and may result in its being caught in the elevated position at the time when it should be in the depressed 60 position.

In the drawings, 5 indicates a substantial casting in the nature of a bracket having the two depending arms 6 and 7, furnished with the diverging open lips 8 and 9, between which 65 access may be had to the slot 10 between the arms. In the arm 6 is formed the vertical slot 11 at right angles with that marked 10, and in this slot 11 are pivoted the upwardly-extending latch 12, working into the slot 10, 70 and the bell-crank lever 13, having the latch 14 at its lower end and the step 15 at its upper end, this upper end extending through the slot 16 in the upper part of the arm 7. In the latch 14 is secured the pin 17, which engages in the slot 18 in the latch 12, so that the movement of the lever 13 will actuate the latch 12. The horizontal end of the bell-crank lever is normally supported by the 75 spring-lifted button 19, working in a socket in the arm 7, the end 15 of this lever being compressible by a plunger or by an equivalent device.

The sustaining-lever 20 is the lever 20 of the patent above referred to, and is adapted 85 to move freely in the slot 10. When in its normal position it is held down by the lower end of the latch 14, but when it is released from this latch the weight of the fender throws it up to the position indicated in dotted lines, 90 when the recovery of the latching mechanism will cause the upper end of the latch 12 to engage this lever and hold it in this position.

The dotted lines 21 show a modified construction which is used when the fender is 95 permanently fastened to the car, the connection formed by this between the arms 6 and 7 serving to strengthen the same.

Having thus described my invention, I claim as new and desire to secure by Letters 100 Patent—

1. In a car-fender, the combination with a

sustaining-lever, of a supporting device, including a latching device, consisting of separate oppositely-disposed and pivotally connected bolts and means for simultaneously actuating the same.

2. In a car-fender, the combination with a sustaining-lever, of a supporting device consisting of a bracket having two members separated at one position for the insertion of the sustaining-lever, and a duplex locking-device mounted to act on the lever between the members.

3. The combination with the bracket 5 having the arms 6 and 7, the arm 7 having the slot 16, the arm 6 having the slot 11, the latch 12 pivoted at the lower end of the slot and

having the slot 18, the bell-crank lever 13 pivoted at the upper end of the slot 11 and having the end 14 provided with the pin 17 extending into the slot 18 of the latch 12 and 20 the step 15 extending beyond the slot 16, and the spring-supported button or rod 19 for normally sustaining the step end of the bell-crank, of a fender-sustaining lever working in the slot between the arms 6 and 7, as and 25 for the purpose described.

In witness whereof I have hereunto set my hand.

ALBERT J. THORNLEY.
